AURÉLIEN DROGO, OF PARIS, FRANCE

CARBURETOR FOR INTERNAL-COMBUSTION ENGINES

Application filed February 20, 1922, Serial No. 538,033, and in France February 28, 1921.

The object of the invention is to provide a carburetor free of the capillary phenomena connected with the usual atomizing nozzle and capable of supplying proper explosive mixtures with both heavy and light distillates.

This invention will be best understood from a consideration of the following detailed description, reference being had to the accompanying drawing.

In the drawings:

Figure 1 is a longitudinal vertical section of the carburetor taken along the line 1—1 of Figure 3.

Figure 2 is a fragmentary vertical section taken along the line 2—2 of Figure 3.

Figure 3 is a horizontal section taken along the line 3—3 of Figure 1.

Figure 4 is a fragmentary vertical section taken along the line 4—4 of Figure 3.

Figure 5 is a fragmentary horizontal section taken along the line 5—5 of Figure 4.

Fig. 6 is a diagrammatic view of the entire carburetor particularly illustrating the relative arrangement and location of the various passages and connections.

Referring more particularly to the drawings, 1 designates a float chamber of the carburetor which includes a float 2 of any approved construction. The float chamber has a cover 2^a at its upper end in which is formed the upper end 3 of a passage which is in communication with a Pitot tube 4, the free end of said tube opening at the mouth of the air intake 6 of the carburetor, with the end 5 being located in the direction of the flow of the air to said motor.

The float chamber 1 is connected by a passage 7 with a suction well 8 which is provided with a plug 9 having a properly diminished aperture 10. Opening above the plug is an end 11 of a fuel intake conduit 12 projecting into a distributor pipe 13 which is connected either directly or through convenient tubes with the inlet passage 14 of the motor. The inlet passage 14 is in communication with air intake 6, the suction being regulated in the said intake by a throttle valve 16 which is controlled through a cam member 20 actuated by a shaft 21. The shaft is operated

in any approved manner through connections with the usual throttle control of an automobile.

In the opening of the intake 6 is arranged the end of a tube 17 which I describe as an up-stream Pitot tube, the said end being directed in an inverse position to the end 5 of the Pitot tube 4 and the said tube 17 through a passage 17^a and a passage 24 in the cover 2^a connects the opening of the intake 6 with the upper part of the well 8 which is provided for feeding the liquid fuel.

The foregoing assembly is diagrammatically illustrated in Figure 6 and functions in the following way:—When the motor is at rest, the end of suction tube 12 is slightly submerged in the fuel contained in suction well 8. As soon as the crank shaft of the motor is turned over to effect a starting operation, the liquid in which the end of tube 12 is submerged will be drawn into the motor and provide a rich starting mixture. When the motor is at idling speed, valve 16 permits the passage of only a limited quantity of air through intake tube 6. The pressure in the float chamber and in the suction well will, therefore, be nearly equal, and fuel will flow from float chamber to suction well by the action of gravity.

The diameter of the aperture in plug 11, and the level of liquid in the float chamber are adjusted so that the extremity of fuel intake conduit 12 is neither completely submerged in, nor entirely above the level of, the liquid in suction well 8 at idling speed. Conduit 12 will thus, deliver an emulsion of fuel and air to the suction side of valve 16. As the speed of the motor is increased, conduit 12 will aspirate fuel more rapidly from suction well 8 and, since aperture 10 in plug 11 limits the rate of flow by gravity of fuel from the float chamber to the suction well, it becomes necessary to provide supplemental means for accelerating the rate of flow of fuel through aperture 10 in proportion to the increasing speed of the motor. This is accomplished by the upstream and downstream Pitot tubes 4 and 17. The increased velocity of the air flowing into air intake conduit 6 reacting on the oppositely directed Pitot tubes, creates a pressure differential in float

chamber 1 and suction well 8 which has the effect of forcing fuel into the suction well at a rate which is a function of the velocity of the air passing through said air intake tube. The 5 Pitot tubes function, therefore, to maintain the liquid in suction well 8 at the same level as at idling speed i. e. so that the end of suction tube 12 is neither submerged in, nor above the level of, the liquid in the suction well. From 10 the foregoing, it is evident that the suction tube will aspirate an emulsion of fuel and air through extremity 11 throughout the range of motor speeds. The suction tube thus replaces, and is in a rough way equivalent to, 15 the nozzle of an ordinary carburetor. It will be noted however, that no capillary phenomena are involved in its operation as is the case with the usual suction nozzle, and as a consequence, none of the usual difficulties at 20 starting and idling speeds are encountered.

Should, for any reason, the level of the float chamber 1 be maintained constant the liquid will flow through the plug 10 with a speed which is proportional to the speed of the air in the suction pipe 6 at the plane passing across the orifice of said pipe. It is possible, when the motor is running slowly, to have the proportion increased by taking the fuel from the level 7°—Y' lower than the level 7°—Y thus having a supplemental charge equal to the depression due to the suction of air at the orifice of the pipe 6. This effect is a trifle at high speeds but it is very noticeable at low speeds as well as when starting the motor. In 35 this manner the starting of the motor is made easier.

The Pitot tube 4 is connected through a passage 22 with passage 3 which is formed in the cover 2^a. A short passage 23 extends 40 downwardly from the passage 3 and opens into the top of the well or float chamber 1 and above the level of the liquid. A valve 26 in the passage 27 which opens into the intake 6 adjacent the valve 16 forms a by-pass from 45 the passage 22 to the intake 6.

The distributor 13 has a perforated end or rose 13^a which is adapted to be disposed within the valve chamber of the internal combustion engine for further breaking up the fuel 50 and air before it enters the engine. It will be appreciated that while I have shown one tube 13 any number may be employed which may be required for the purpose.

It may happen that owing to the special 55 arrangement of the motor it may be possible to directly bring to the valve chamber the emulsion of liquid fuel and air. In this instance the suction pipe 12 will open directly into the pipe 6 at a convenient point between the throttle 16 and the motor. In this construction the valve 26 will be opened for placing the passage 3 directly in communication with the intake 6 at a point adjacent the valve 16 and through the passage 27.

65 What I claim is:

1. A carburetor comprising in combination an air intake conduit, a valve controlling said conduit, a well having an opening in the wall thereof communicating with the atmosphere, a fuel conveying system including a passageway having one extremity communicating with said well and the other extremity communicating with said air intake conduit, said passageway being separate from, and independent of, said opening in the wall of the well, a fuel reservoir communicating with said well through an orifice of predetermined dimensions and means operable to vary the flow of fuel through said orifice in accordance with variations of the velocity of the air flowing 70 into the air intake conduit. 75

2. A carburetor comprising in combination an air intake conduit, a valve controlling said conduit, a suction well having an opening in the wall thereof communicating with the atmosphere, a suction conduit having one extremity terminating inside the suction well and another extremity in communication with the air intake conduit, said suction conduit being separate from, and independent of, the 85 opening in the wall of the suction well, an enclosed fuel supply chamber communicating with said suction well, and means including a Pitot tube for varying the pressure in said fuel supply chamber in accordance with variations of the velocity of the air flowing into 90 the air intake conduit. 95

3. A carburetor comprising in combination an air intake conduit, a valve controlling said conduit, an enclosed suction well, a suction conduit having one extremity terminating inside the suction well and having another extremity in communication with the air intake conduit, a fuel supply chamber communicating with said suction well, and means 100 including a Pitot tube for varying the pressure in the upper part of the suction well in accordance with variations of the velocity of the air flowing into the air intake conduit. 105

4. A carburetor comprising in combination an air intake conduit, a valve controlling said conduit, a suction well, a constant level chamber communicating with said suction well through an orifice of predetermined dimensions, a suction conduit having one extremity in communication with the air intake conduit and having another extremity terminating inside the suction well, an upstream Pitot tube positioned in the air intake conduit and extending to the upper part of the constant level chamber, and a downstream Pitot tube positioned in the air intake conduit and extending to the upper part of the suction well. 115 120

5. A carburetor comprising in combination an air intake conduit, a valve controlling said conduit, a well having an opening in the wall thereof communicating with the atmosphere, a suction conduit having one extremity terminating inside the well and having another extremity communicating with the air intake 125 130

conduit at a point situated downstreamward with relation to said valve, said suction conduit being independent of the opening in the wall of said well, and a fuel reservoir communicating with said well through an orifice of predetermined dimensions.

6. A carburetor as defined in claim 5 in combination with means including a Pitot tube for varying the rate of flow of fuel through said orifice in accordance with variations of the velocity of the air flowing into the air intake conduit.

In testimony I have hereunto set my hand at Paris, France, this 3d day of February, 1922.
